VENDING MACHINE FOR PACKAGED LOAVES OF BREAD

Otto C. Kroopp, Chicago, Ill., assignor to The Peterson
Oven Company, Franklin Park, Ill., a corporation of Illinois

Application August 22, 1955, Serial No. 37,603

Term of patent 3½ years
(Cl. D52—3)

The single figure is a front perspective view of a vending machine for packaged loaves of bread, showing my new design.

The undisclosed side of the vending machine is the same in appearance as the side shown in the drawing.

I claim:

The ornamental design for a vending machine for packaged loaves of bread, substantially as shown and described.
